CLAIM

The ornamental design for a pruning shears with axial offset handles, as shown and described.

DESCRIPTION

FIG. 1 is a front perspective view of a first embodiment of the pruning shears showing the cutting blades in an open configuration;

FIG. 2 is a front perspective view of the pruning shears of FIG. 1 showing the cutting blades in a closed configuration; FIG. 3 is a side elevation view of the pruning shears of FIG. 2;

FIG. 4 is a top plan view of the pruning shears of FIG. 2; FIG. 5 is a bottom plan view of the pruning shears of FIG. 2;

FIG. 6 is a front perspective view of a second embodiment of the pruning shears;

FIG. 7 is a front perspective view of the pruning shears of FIG. 6 showing the cutting blades in a closed configuration; FIG. 8 is a side elevation view of the pruning shears of FIG. 7;

FIG. 9 is a top plan view of the pruning shears of FIG. 7; and,

FIG. 10 is a bottom plan view of the pruning shears of FIG. 7.

The portions of the pruning shears shown in broken lines form no part of the claimed design.

The shaft of the pruning shears with axial offset handles is shown with a symbolic break in its length. The appearance of any portion of the article between the break lines forms no part of the claimed design.

1 Claim, 10 Drawing Sheets
